UNITED STATES PATENT OFFICE.

SAMUEL E. JARVIS, OF LANSING, MICHIGAN.

PORTABLE STEAM ENGINE AND BOILER.

SPECIFICATION forming part of Letters Patent No. 267,792, dated November 21, 1882.

Application filed August 10, 1882. (No model.)

To all whom it may concern:

Be it known that I, SAMUEL E. JARVIS, of Lansing, in the county of Ingham and State of Michigan, have invented new and useful Improvements in Portable Steam Boilers and Engines; and I do hereby declare that the following is a full, clear, and exact description thereof, reference being had to the accompanying drawings, which form a part of this specification.

10 The nature of this invention relates to certain new and useful improvements in the construction of that class of steam engines and boilers known as "portable;" and the invention consists in the peculiar construction of 15 parts and their various combinations, as more fully hereinafter described.

20 The objects of this invention are, first, to so construct the boiler that it can be easily flushed and thoroughly cleaned; second, to so set the 25 boiler by means of proper appliances that the fire-box will be entirely surrounded by water; third, to provide a steam space and dome of a novel construction; fourth, to provide means for easily attaching and removing the engine, so that the two may be more readily transported and handled.

Figure 1 is a perspective view of my improved portable engine and boiler set up and ready for use. Fig. 2 is a vertical longitudinal central section through the boiler.

30 In the accompanying drawings, which form a part of this specification, A represents the timbers upon which the whole rests. Upon these timbers the iron cross-girts B are secured. These girts project upon one side of the boiler to form the bed plates or supports for the engine-frame C, which carries the cylinder and working-parts of said engine. The projecting parts of these girts are shown at a, 35 and the engine-frame is secured to them by bolts b, one near each corner of the frame, so that for the purposes of transportation the engine may be readily detached by removing said bolts.

40 D represents the boiler, which is of tubular form and provided with a tubular fire-box, E, from which the flues lead to the smoke-jacket in the usual way. Secured by riveting to the bottom of the boiler are the saddles F and G, 45 the former being shorter than the latter in order to give the boiler an inclination to the

front by elevating the rear end thereof by the higher saddle, which is placed under the rear end of the boiler, as shown. By this peculiarity of setting, when the boiler contains 55 the proper amount of water the fire-box is entirely surrounded by the water, and a steam-space is left at the rear end of the boiler above the water-line. The steam-dome G' is secured on top of the boiler near the rear end thereof, 60 and a perforated T-shaped pipe leads from the steam-space up into the dome and conducts the steam into said dome, from which it is taken out for use through the pipe H. In order to allow any water of condensation that 65 may collect in said dome to escape back into the boiler, the latter is perforated within the dome and around the pipe leading into the same. At the rear end of the boiler there is a man-hole, a', covered by the smoke-jacket J, 70 and in the bottom of the boiler, and at its front end, is another man-hole, b. The position of the boiler compels all sediment to settle near this latter-described man-hole, whence such sediment can easily be withdrawn, and if it is 75 desired to flush out the boiler it can readily be done by water admitted at the rear man-hole, allowing it to escape freely through the front one. The sheets forming the front of the boiler are cut out to allow the fire-box to 80 be inserted, and the cut edges are bent outwardly to form an annular flange, c, which is riveted to the wall of the fire-box, so that the latter, which is not built into the boiler in the usual way, can be readily removed for repairs, 85 when necessary, by simply cutting off and removing the securing-rivets and disengaging the flues. I is the fire-front, provided with the usual feed and draft doors, and cast with a flange adapted to engage with the projecting 90 flange to which the fire-box is secured.

The engine is of the usual construction; and L is a support for the pillow-block of the main shaft K, which passes beneath the boiler and carries the fly-wheel or driving-pulley on the 95 opposite side of the boiler to that shown in the drawings. This support L is removably secured to the timber or to the end of the front girt.

I find it very objectionable to bolt the carrying saddles to the boiler, on account of the difficulty of preventing leaking at that point, so I

rivet them fast before shipping from the shops. When a large boiler and engine are required of a portable character, larger than ordinarily constructed, on account of the difficulties in shipping, especially where transportation must be by means of wagons and teams, my construction will be found very valuable, because of the ease with which the engine can be detached, so as to divide into two loads, and to set up the whole only requires that the timbers be leveled and the boiler placed upon them, when the engine will be found in perfect working order, requiring no skilled labor to put it up.

15 I attach importance to the fire-box being removable, and when in position being entirely surrounded by water, in its relation to the flues and boiler, and its manner of being secured in place to the flange *c*.

20 What I claim as my invention, and desire to secure by Letters Patent, is—

1. In a portable steam-boiler having rigid supports of different heights and a steam-dome located near its highest end over perforations in the shell of said boiler, and adapted to allow 25 the return thereto of the water of condensation, and a perforated pipe located below and extending into said dome and adapted to convey the steam thereinto, substantially as set forth.

2. In combination with a portable steam-boiler, constructed and operating substantially as described, and provided with rigidly-attached saddles of different heights, the iron girts performing the double office of supporting the boiler and the engine, substantially as 30 35 and for the purposes set forth.

SAMUEL E. JARVIS.
